UNITED STATES PATENT OFFICE.

CHARLES V. SHIPLEY, OF SAN LEANDRO, CALIFORNIA, ASSIGNOR TO J. H. RIDING, OF OAKLAND, CALIFORNIA.

ATTACHMENT FOR TYPEWRITERS AND THE LIKE.

Application filed January 19, 1925. Serial No. 3,315.

To all whom it may concern:

Be it known that I, CHARLES V. SHIPLEY, a citizen of the United States, residing at San Leandro, in the county of Alameda and State of California, have invented certain new and useful Improvements in Attachments for Typewriters and the like, of which the following is a specification.

This invention relates to attachments for typewriters and the like, and more particularly to an eraser device for typewriters wherein the eraser is always at hand for immediate use.

Stenographers and others using typewriters usually have daily need for an eraser for the correction of errors, and it is of more or less constant occurrence to spend much time in the search of an eraser that is somewhere upon the desk and usually not in any particular place; therefore, a search among and under papers is the common procedure in quest of the eraser, and consequently time is consumed with a corresponding loss of productive work.

Having the above in view, the primary object of my invention is the production of a separate and salable inexpensive article of manufacture, in the form of a compact eraser device easily attachable to typewriters and wherein the eraser may be withdrawn from a station and automatically returned thereto, and consequently when the eraser is not in use it will always be found at the same spot. Another important object is that the device is of such design as to render the mechanism easily accessible; and a further object is to provide the device with a cover having means whereby the cover may be easily turned to regulate the tension for the return of the cord member of the device.

The invention possesses other advantageous features, some of which, with the foregoing, will be set forth at length in the following description where I shall outline in full that form of the invention which I have selected for illustration in the drawings accompanying and forming part of the present specification. In said drawings I have shown one form of my invention, but it is to be understood that I do not limit myself to such form, since the invention, as expressed in the claims, may be embodied in a plurality of forms.

Referring to said drawings:

Figure 1 is a front view of my invention shown in connection with a portion of a typewriter. Part of the housing of the invention is broken away to show the compactness of the reeled spool therein.

Fig. 2 is a vertical section through the device with the omission of the operating mechanism.

Fig. 3 is a face view of one side of the cover for the housing.

Fig. 4 is a face view looking into the housing; the dot-and-dash lines indicate the position of a pawl in holding engagement.

Fig. 5 is a face view of one side of the spool showing pivoted pawls in the recess of the spool; the pawls are shown in the out-of-engagement position.

Fig. 6 is a section through the center of the spool showing the mechanism compactly housed within the spool.

Fig. 7 is a view similar to Fig. 5 but of the reverse side of the spool and showing the nested coil spring; and Fig. 8 is a face view of either end of the coil spring showing the eye for pin engagement.

Fig. 9 is a perspective view of one of the pawls and its projecting stud.

I will now describe my invention in detail by reference numerals: 10 in Fig. 1 represents a corner post or other boundary part of a typewriter, and 11 the supporting surface for the typewriter.

12 is a plate or frame preferably of sheet material and on which the invention is built. 13 is an anchoring foot formed by bending the plate, and the extreme end of the foot may be chamfered as shown at 14 to allow the foot of the device to be easily pressed under the typewriter post 10, thus the said foot forms a convenient attachment member in this case.

To the upper end of the plate is mounted and secured, as by soldering, a section of cylindrical tubing 15 formed with a recessed open end 16. This construction forms a housing for the mechanism of my invention, and which housing is completed by a cover 17 adapted to be snugly pressed into the recess 16.

Within the housing is rotatably supported a spool 18 having a grooved cylindrical surface 19 and recessed faces 20 and 21, and central journals 22 and 23. The latter are

supported in bearings 22' and 23' formed as part of the plate 12 and cover 17 respectively.

In the recess 20 of the spool is mounted 5 a pair of pawls 24 and 25 each provided with a projecting stud 26 at one end for pivotal movement in apertures 27 in the body wall of the spool. The other end 28 of each pawl is made heavy to insure the tooth 29 thereof 10 dropping by gravity, when in service, into the indent 30 in the bearing 22' of the plate. In the recess 21 of the spool is nested a coil spring 31 having at each end an eye 32. One eye of the spring is hooked over the pin 33 15 in the spool, and the other eye is engaged by the pin 34 fixed in the bearing 23' of the cover and which bearing has a chamfered end 39, and the manner of engagement will be later described.

20 A suitable cord 35 is attached to the spool in the hole 36 in the wall of the recess 20, and wound in the groove 19 of the spool and passed through a suitable opening 37 in the housing. To the other end of the cord is 25 attached an instrument such as an eraser 38.

In assembly and operation, the spool is wound and with the pawls and spring there- 30 in the spool is slipped in the housing and bearing 22', then the bearing of the cover is slipped over the journal 23 and between it and the unengaged end of the coil spring, the chamfered end 39 of the bearing pushing a clearance for the pin 34 when the cover 35 is turned to engage the said pin in the eye of the spring, and the cover is then pressed 40 into the recess. The eraser may then be pulled out, and if the spring tension for the return of the eraser is insufficient, an instrument such as a nail may be inserted in the notch 40 of the cover (Fig. 3) and the latter turned thereby in the direction of the arrow until the desired tension is attained. When 45 the desired length of cord is unwound for service, the tooth of the uppermost pawl

45 drops by gravity into the indent therefor (Fig. 4); and to accomplish the return of the eraser, simply give a quick short pull on the cord and centrifugal force induced by the spring, will keep the pawls out of engagement with the indent.

50 Having illustrated and described the preferred form of my invention, what I claim as new and desire to secure Letters Patent thereon is the following:

55 In a device of the class described, a sheet-metal supporting frame comprising an upright portion and a horizontal anchoring foot portion, the upright portion having a relatively large area at the top thereof, a housing carried by the upper end of the 60 upright portion, one side of said housing closed by a fitted cover plate and the opposite end closed by the said area of the upright portion, a spool in said housing, said spool provided with journals, a bearing 65 formed in the upright portion and in said cover plate for the said journals, said spool having an attached cord adapted to carry an eraser on the free end thereof, the cord being wound upon the spool and adapted to unwind therefrom through an opening in the housing, spring means supported in the spool and to the cover plate to restrain the cord in the unwinding therefrom, and further means supported in the spool to check 75 and hold a desired length of the cord unwound from the spool, said latter means consisting of a pivoted pawl having a tooth adapted to engage an indent in the said upright bearing, and the said cover plate pro- 80 vided with an opening for the insertion of means to turn the cover to tighten the said spring restraining means when the spring becomes weak through service.

85 In testimony whereof, I affix my signature.

CHARLES V. SHIPLEY.
